[57] CLAIM

The ornamental design for a money clip alarm unit for cash registers and the like, substantially as shown.

DESCRIPTION

FIG. 1 is a top plan view of a money clip alarm unit for cash registers, and the like, illustrating my design;

FIG. 2 is a side view;

FIG. 3 is one end view;

FIG. 4 is another end view; and

FIG. 5 is a bottom view.
